UNITED STATES PATENT OFFICE.

HENRY W. O'NEILL, OF ELMHURST, NEW YORK, ASSIGNOR TO WESTERN ELECTRIC COMPANY, INCORPORATED, OF NEW YORK, N. Y., A CORPORATION OF NEW YORK.

COMPOSITE RINGER CIRCUITS.

Application filed October 22, 1924. Serial No. 745,088.

This invention relates to composite ringer sets for relaying low frequency currents into currents of high frequency and vice versa.

5 Composite ringer sets are quite generally interposed between a line and a switchboard on composited, repeated and other similar line circuits, and serve to prevent low frequency signaling or ringing currents 10 from reaching telegraph apparatus on composited circuits, and also to apply current at higher frequencies to telephone circuits in order that the current may traverse the telephone circuits without excessive attenuation. 15 A standard type of composite ringer set now in general use is adapted to relay the usual switchboard ringing current of 16 or 20 cycles per second to current at 135 cycles per second at the opposite or line side 20 of the set while inversely 135 cycle current incoming at the line side of the set is relayed to 16 or 20 cycle current at the switchboard side of the set.

25 Heretofore it has been the practice to employ sources of alternating current which comprise equipment or units separate and distinct from the composite ringer sets themselves. For example, for ringing in one direction, the application of current from a 16 or 20 cycle source effects responsive relays to switch the line circuit from the switchboard circuit to a source of 135 cycle current while for signaling in the opposite direction, current from a 135 cycle 35 source effects the response of other relays to switch the switchboard line from the external line to a source of 16 or 20 cycle current.

40 With the composite sets as hereinbefore described dependent upon separate sources of ringing current at the sets, it has not been possible to employ composite ringers except where such separate sources of current are available. Thus, the use of such sets has been limited to such points where the traffic load is heavy enough to warrant the installation of ringing generators. In accordance with the present invention, it is proposed to dispense with the separate sources of current and to provide that relays may serve as vibrators to effect the generation of alternating current at proper frequencies for carrying out the necessary signaling operations. The composite set is

thus rendered complete within itself and enables the use of the set at any isolated point or at points where, due to lower traffic loads during the night, Sundays or at other times, it becomes inadvisable to maintain the power equipment in continuous operation. 55

60 It is the object of the present invention to provide a composite ringer set which shall be complete within itself, independent of outside ringing current and economical to install and operate. 65

70 The object of the invention is attained through the employment of a vibrator relay of a type which short-circuits its own windings. Vibrators of this type are free from contact chatter and substantially unaffected by current overloads, have little or no tendency to spark at contacts, are easily adjusted and have large energy output as distinguished from vibrators of the interrupter type which have heretofore been proposed. 75 The vibrator relay is arranged to be common to a plurality of composite sets so that a single relay may serve as a means for generating signaling current for all or a part of the composite sets of a switching station. 80

85 It is believed that the invention will best be understood from a consideration of the drawings and the following detailed description thereof.

Fig. 1 shows one of a plurality of composite ringer sets and a vibrator relay which is arranged common to the plurality of sets and arranged to serve the sets in groups. 90

Fig. 2 taken in connection with that portion of Fig. 1 above the dot and dash lines shows a modification in which the common vibrator relay is inductively coupled to the several composite sets which it serves. 95

Fig. 3 when taken in connection with that portion of Fig. 1 to the left of the dot and dash line, is a further modification showing a different manner of associating a common vibratory relay with several composite sets of the repeating coil type. 100

Fig. 4 shows a composite set with a polarized relay which serves as both a responsive device and a transmitting device and circuits for rendering the polarized relay, when serving as a transmitting device, controllable by a master vibrator which is common to a plurality of composite sets. 105

Fig. 5, when taken in connection with that

portion of Fig. 4 to the left of the dot and dash line, shows a modified form of the circuit as shown in Fig. 4.

Referring first to Fig. 1, a line circuit is shown at 1-2 outgoing from the composite set, and a switchboard line 3-4 extending from the set to a switchboard of an exchange system. Inasmuch as the invention is not concerned with the particular structure and operation of the outgoing line and switchboard, they have not been disclosed herein. A source of 20 cycle ringing current is shown at 5 and a vibratory relay at 6 which is capable of responding to 135 cycle current in coming over the line 1-2. A master vibrator relay 16 which is adjusted to vibrate at a frequency of 135 cycles is arranged for association with a plurality of groups of composite sets through transformers 11, 19 and 20 which are common respectively to the several groups of composite sets.

In the operation of the circuit as shown in Fig. 1, low frequency signaling current of, for example, 20 cycles applied to the switchboard line 3-4 flows over conductor 3, the upper back contact of switching relay 7, through the retardation coil 12, condenser 13, alternating current relay 9, which is adjusted to respond to signaling current of 20 cycles frequency, lower back contact of relay 7 to conductor 4. Relay 9 responds and establishes a circuit from ground at the normally closed contact of relay 10, through the contact of relay 9 and thence to battery in parallel, through the windings of relays 8 and 14. It is to be noted that relay 10 is normally maintained energized over a circuit extending through the normally closed contact of relay 6. Relay 8 upon energizing disconnects the conductors of line 1-2 from the talking conductors of the composite set, and connects the conductors of line 1-2 with the upper winding of transformer 11. This transformer, as indicated by the multiple taps is common to all of the composite sets of a group. Relay 14, upon energizing, establishes a holding circuit for relay 10 independent of the contacts of relay 6 and at its lower contact establishes an energizing circuit for the master vibrator relay 16 which may be traced from battery through the windings of relay 16, the lower winding of transformer 11 to ground at the lower contact of relay 14. Relay 16 energizes in this circuit closing a shunt about its own windings and thereby causing a surge of current through the lower winding of transformer 11 each time that relay 16 energizes. These surges of current induce a flow of alternating current through the upper winding of transformer 11 and thence out over the line 1-2.

It is to be noted that the master vibrator relay 16 may serve other groups of com-

posite circuits through the windings of transformers 19 and 20. In employing several transformers as shown, a more uniform potential condition for the 135 cycle current may be had during periods of heavy ringing current load, while economy of energy and increased life of vibrator contacts may be had, due to the fact that on the light ringing current loads a single transformer may alone be under energization at one time rather than energization of a large transformer unit capable of supplying a maximum load.

A condenser 17 is connected in shunt of the lower winding of transformer 11 and serves to increase the energy in the associated output circuit of the transformer and overcomes any tendency of the vibrator contacts to spark and also serves for effecting any predetermined correction or bettering of the wave form of the generated ringing current.

In response to signals of 135 cycle current incoming over line 1-2, the relay 6 responds in phase with the incoming current. This current flows over conductor 1, the upper back contact of relay 8, retardation coil 12, condenser 18, windings of relay 6, the lower back contact of relay 8 and thence over conductor 2. A condenser 15 in bridge of the windings of relay 6 serves to render the relay 6 resonant to the incoming signaling current. Relay 6 in response to the signaling current, intermittently opens its contacts at such a rate that the effect is as if a high resistance were inserted in the circuit at this point and since, at this time, relay 14 is deenergized, the circuit of relay 10 is modified and relay 10 thereupon deenergizes closing an obvious circuit for relay 7. Relay 7 upon energizing disconnects the limbs of the switchboard line 3-4 from the talking conductors of the set and connects the line 3-4 to the source 5 of 20 cycle ringing current.

Considering the modified form of the invention as shown in Fig. 2, it will be noted that an output transformer 22 is employed common to a plurality of composite sets. In response to 20 cycle signaling current applied from the switchboard over line 3-4, the circuit functions as previously described in connection with Fig. 1 up to and including the operation of relay 14. When relay 14 energizes, an operating circuit is established for the vibrator relay 21 extending from ground to a point in the lower winding of transformer 22 and through the left portion 41 of this winding to battery. The transformer is thereupon magnetized to cause a half wave of current to rise in the upper winding 43 which is transmitted to line 1-2, over the front contacts of relay 8. At the same instant, a circuit is closed through the right lower winding 42 of the

transformer, inversely wound to winding 41, thence through the winding of relay 21 to battery. The response of relay 21 closes a short circuit about itself establishing full potential across the terminals of winding 42. With winding 42 wound with more ampere turns than winding 41, the magnetic effect produced by winding 42 overbalances that produced by winding 41 and a second 5 half wave of opposite polarity rises in the upper winding 43 and is transmitted to the line 1-2. On the collapse of energy in the winding of relay 21 due to the closure of its contacts, release of the armature and operation 10 of its contacts effects a substantial cessation of the current in the transformer winding 42 as the resistance of relay 21 is high. The current still present in the winding 41 of the transformer now neutralizes 15 the residual magnetization and causes flux to build up in the first or opposite polarity direction. This causes the second half wave of induced current to fall and be followed by rise of a half wave in the opposite direction. 20 Such cycle of changes continue in phase with the frequency of vibrator 21 whose armature is tuned to a natural period of 135 cycles and whose winding is shunted by a resistance 24 and condenser 23 in series 25 for the purpose of preventing sparking at the contacts of the relay and for providing a resonating path for the relay. 30

As indicated at 26, the transformer 22 may be provided with an electrostatic shield 35 connected to ground whereby the winding 43 may be isolated relative to mutual capacity effects from the windings 41 and 42. In the general use of the system, however, this shielding may be omitted.

Referring to Fig. 3 taken in connection 40 with that portion of Fig. 1 to the left of the dot and dash line, a common vibrator tuned to operate at 135 cycles frequency is shown in the enclosed rectangle for supplying 135 cycle signaling current to a plurality of composite sets. In the composite set disclosed, a 45 repeating coil of the usual type is employed to effect an inductive coupling between the switchboard and outgoing line conductors.

When 20 cycle signaling current is applied 50 at the switchboard to the line 3-4, the current flows over conductor 3, the back contact of relay 7, the upper left winding of repeating coil 50, relay 9, condenser 13, the lower left winding of coil 50, the lower back contact of relay 7 to conductor 4. Relay 9 energizes, in turn establishing an operating circuit for relays 8 and 14. These relays function in identically the same manner as 55 previously described in connection with the circuit of Fig. 1 to hold relay 10 operated, disconnect the limbs of line 1-2 from the right windings of repeating coil 50 and connect them to the upper winding of transformer 25 and to start the common vibrator 60

relay 21 into operation. Upon the initial energization of relay 14 with relay 21 deenergized, a circuit is closed from ground through the winding 44 of transformer 25 and winding of relay 21 in parallel therewith, thence 70 through the winding 45 of the transformer to battery. If the two windings 44 and 45 are wound to differentially balance each other under these conditions, no current is induced in the upper winding of the transformer 75 25. Since relay 21 energizes in this circuit, it shunts its own winding thereby causing an increased flow of current through the winding 44 overbalancing the effect of winding 45. Current is thereby induced in 80 the upper winding of the transformer and flows to the line 1-2 as a half wave of one polarity. As soon as relay 21 shunts its winding, however, it deenergizes, again restoring the windings 44 and 45 to their initial 85 condition whereby current is induced in the upper winding of the transformer and flows as a half wave of the opposite polarity to the line 1-2. Thus, as relay 21 vibrates at a frequency of 135 cycles, to which its 90 reed armature is tuned, a signaling current is transmitted to line 1-2 in phase with the vibratory operation of relay 21. A resistance 24 and condenser 23 connected from the 95 circuit of relay 21 to ground serve to prevent sparking at the contacts of relay 21.

If desired, the windings 44 and 45 of transformer 25 may be proportioned similarly to the windings 41 and 42 of transformer 22 (Fig. 2), the winding 44 having a greater number of ampere turns than winding 45. With windings wound in this manner, when relay 14 energizes, the current flowing through the winding 44 in series with winding 45 will cause the winding 44 105 to overbalance the winding 45 and produce a flux which will cause current of one polarity to flow from the upper winding of transformer 25 to the line 1-2. At the same instant, relay 21 energizes short circuiting its own winding and the winding 44 thereby withdrawing the overbalancing effect of winding 44, whereby winding 45 is enabled to produce current in the upper winding of transformer 25 in the opposite polarity direction. This cycle of operations is then 110 repeated in phase with the vibration of relay 21.

When a signal is incoming to the composite set from line 1-2, 135 cycle signaling current flows from conductor 1 over the upper back contact of relay 8, through the upper right winding of repeating coil 50, both windings of relay 6, the lower right winding of repeating coil 50, the lower back contact of relay 8, back over conductor 2, causing the energization of relay 6 which is tuned to respond to current of 135 cycles frequency. Relay 6 in operating opens the circuit of relay 10 thereby causing the energization of relay 7 and the application of low frequency 120 125 130

current from source 5 to the switchboard line 3-4.

In Fig. 4, relay 6 is of the same type as similar relays shown in the modifications 5 previously described and is under the control of a master vibrator 36 of the same type. As indicated by the multiple connections, the master vibrator relay 36 is common to a plurality of composite sets. When 10 low frequency signaling current is applied at the switchboard to the conductors of line 3-4, the relay 9 which is bridged across the conductors 3-4 through the retardation coil 12 and condenser 13, through 15 the back contacts of relay 7, responds and establishes an obvious circuit for relays 8 and 14. Relay 8 upon energizing disconnects the talking conductors of the composite set from conductors 1 and 2 of the outgoing line and bridges the right winding 20 of transformer 31 across conductor 1 and 2 through condenser 32. In addition, relay 8 opens the circuit of relay 27 to prevent its false operation at this time and prepares a 25 circuit for relay 6. Relay 14 upon energizing closes an operating circuit for the master vibrator relay 36 extending from battery through both windings of relay 36 to ground at the lower contact of relay 14. 30 The vibrator relay thereupon attracts its armature placing a short circuit about its own windings, whereupon it deenergizes and then continues to repeat this cycle of 35 operations so long as relay 14 remains energized. With relays 8 and 14 both energized a circuit is closed for relay 6 extending from battery through the middle upper front contact of relay 14, both windings of 40 relay 6 to ground at the upper alternate contact of relay 8. Relay 6 upon energizing in this circuit closes a circuit from ground at its contacts through the upper front contact of relay 8, the left winding of transformer 31 to battery through the innermost upper 45 front contact of relay 14. The surge of current thus produced in the left winding of transformer 31 is induced in the right winding thereof and flows as a half wave of alternating current out over the line 1-2. 50 When relay 36 shunts its windings, a shunt is established thereby around the windings of relay 6, this shunt extending from the ground at the uppermost contact of relay 8 through the windings of relay 6, the upper 55 middle front contact of relay 14, the contacts of relay 36 to ground at the lower contact of relay 14. This shunt causes the de-energization of relay 6 and the opening of the circuit through the left winding of 60 transformer 31 whereby current is induced in the right winding of transformer 31 to produce a half wave of alternating current of the opposite polarity over line conductors 1-2. In this manner, as relay 36 vibrates, 65 alternating current is transmitted to the line

1-2 in phase with the vibratory action of relay 36. Since relay 36 is tuned to operate at a frequency of 135 cycles, the outgoing signaling current will be of 135 cycles. To absorb the surges from the transformer 70 31 and thereby protect the contacts of relay 6, a condenser 34 is connected in shunt of the left winding of transformer 31 over the innermost upper front contact of relay 14. This condenser also serves to increase the 75 output and improve the wave form of the alternating current produced.

When a signaling current of 135 cycles frequency is incoming over the line 1-2 with relays 8 and 14 both deenergized, this 80 current flows from conductor 1 through condenser 32, the right winding of transformer 31, the innermost upper back contact of relay 14, the left winding of transformer 31, the uppermost back contact of relay 8, both 85 windings of relay 6, middle upper back contact of relay 14, middle back contact of relay 8 to conductor 2. Relay 6 energizes in this circuit and at its front contact closes a circuit from ground over the lower back contact of relay 8, resistances 28 and 29, winding of relay 27 to battery. This energization of relay 6 at the rate of 135 cycles producing an intermittent closure of the circuit of relay 90 27 produces a local current in the circuit comprising the winding of relay 27, resistance 28 and condenser 30 which is sufficient to maintain relay 27 energized. Relay 27 operates, shunting the winding of relay 10 which upon deenergizing operates relay 7. 100 Relay 7 upon energizing disconnects the talking conductors of the set from the switchboard line 3-4 and connects the source of low frequency ringing current 5 with the conductors of line 3-4. Condenser 105 30 in conjunction with resistance 28 in shunt of the winding of relay 27 effects a steady energization of relay 27 during the period that relay 6 is operating in response to incoming signaling current. The condenser 110 32 in the energizing circuit of relay 6 serves for effecting a condition of series resonance for relay 6 while the condenser 34 which is connected in shunt of the winding of relay 6 through the uppermost back contact of 115 relay 14 effects parallel resonance for relay 6 with respect to signaling current at 135 cycles.

Fig. 5 taken in connection with that portion of Fig. 4 to the left of the dot and dash line shows a further modification employing a master vibrator relay 35 common to a plurality of composite sets. For an outgoing signal ringing current applied over the switchboard line 3-4 causes the operation of relay 9 and the energization of relays 8 and 14 in the manner previously described. Relay 8 upon energizing disconnects the limbs of outgoing line 1-2 from the talking conductors of the composite set, 120 125 130 135

connects the right winding of transformer 31 to the limbs of line 1—2 and in conjunction with relay 14 prepares energizing circuits for relay 6 and 35. The energizing circuit of relay 35 may be traced from ground through the winding of this relay, resistance 40, lower front contact of relay 14 to battery. The circuit of relay 6 may at this time be traced from battery through the lower front contact of relay 14, the upper front contacts of this relay, the windings of relay 6, the lowermost front contact of relay 8, to ground through the winding of relay 35. The winding of relay 35, however, is of such resistance that relay 6 which is connected in parallel with resistance 40 does not receive sufficient current to cause its operation at this time. Relay 14 in addition to the functions above described, opens the circuit of relay 27 at the lower back contact of relay 14 to prevent its false operation when relay 6 energizes as later described.

As soon as vibrator relay 35 energizes, it closes a circuit about its own winding thereby reducing the resistance in the circuit of relay 6 to such an extent that relay 6 operates. Upon the energization of relay 6 a circuit is closed from ground through the left winding of transformer 31, contacts of relay 6, upper front contacts of relay 14, lower front contact of relay 14 to battery. The surge of current in the left winding of transformer 31 induces a half cycle of alternating current in the right winding of transformer 31 which flows out over line 1—2. As soon as vibrator relay 35 short circuits its own winding it becomes deenergized, again introducing the resistance of its own winding in the operating circuit of relay 6 thereby causing relay 6 to de-energize. The deenergization of relay 6 opens the circuit through the left winding of transformer 31 thereby inducing a half wave of alternating current in the right winding of transformer 31 which flows in the opposite direction over line 1—2. Vibrator relay 35 continues to operate in the cycle above described at a frequency of 135 cycles to which its reed armature is tuned, thereby producing an alternating current of the same frequency in the line 1—2. The condenser 33 connected in shunt of the left winding of transformer 31 effects a reduction of the sparking at the contacts of relay 6 and tends to smooth out the wave form of the alternating current transmitted over line 1—2.

For an incoming signal with relays 8 and 14 both deenergized, alternating current of 135 cycles frequency flows from conductor 1 over the upper back contact of relay 8, impedance coil 38, condenser 39, lowermost back contact of relay 8, windings of relay 6, upper back contact of relay 14, middle

back contact of relay 8 to conductor 2. Relay 6 in responding to this alternating current closes a circuit for relay 27 extending from battery at the lower back contact of relay 14 through the winding of relay 27, resistances 28 and 29, contacts of relay 6 to ground through the left winding of transformer 31. Relay 27 upon energizing causes the application of low frequency ringing current from the source 5 to the switch-board line 3—4 in the manner described in connection with Fig. 4. The condenser 39 connected serially in the circuit of relay 6 effects series resonance for the relay 6 and condenser 37 which is connected in parallel with the windings of relay 6, effects parallel resonance relative to the control of relay 6 at 135 cycles frequency.

During the reception of incoming signals from the line 1—2, the master vibrator relay 35 is functionless with respect to the particular composite set which is receiving the incoming signals but may be at the time functioning to produce outgoing signals in connection with other composite sets.

What is claimed is:

1. In a telephone exchange system, a plurality of lines and means for applying signaling current to said lines comprising a vibratory relay individual to each of said lines, means for inductively associating said relays with the lines to which they are individual, and a master vibrator relay common to said relays and controlling the vibratory operation thereof, said master relay having short circuiting contacts for causing its own vibratory operation.

2. In a telephone exchange system, a plurality of lines, and means for applying signaling current to said lines comprising a vibratory relay individual to each of said lines, means for inductively associating said relays with the lines to which they are individual, and a master vibrator relay common to said relays, said master relay having short circuiting contacts for controlling its own and the vibratory operation of said other relays.

3. In a telephone exchange system, a plurality of lines, a relay individual to each of said lines responsive to signaling current of a predetermined character incoming or outgoing over said lines, means for inductively associating said relays with the lines to which they are individual, and means comprising a master vibrator relay common to said relays and controlling the vibratory operation thereof, said master relay having short circuiting contacts for causing its own vibratory operation and said first relays when functioning under the control of said master relay cooperating with said inductive means to generate and apply signaling current of said predetermined character to said lines.

4. In a telephone exchange system, a plurality of lines, a relay individual to each of said lines responsive to signaling current of a predetermined frequency incoming or outgoing over said lines, means for inductively associating said relays with the lines to which they are individual, and means comprising a master vibrator relay common to said relays and controlling the vibratory operation thereof, said master relay having short circuiting contacts for causing its own vibratory operation and said first relays when functioning under the control of said master relay cooperating with said inductive means to generate and apply signaling current of said predetermined frequency to said lines, and means for resonating said relays to said predetermined frequency.

5. In a telephone exchange system, a plurality of lines, and means for applying signaling current to said lines comprising a vibrator relay and a transformer individual to each of said lines, circuits extending through one winding of each of said transformers and the contacts of the associated relay, means for connecting the other windings of said transformers with the associated lines, and a master vibrator relay common to said relays for controlling the vibratory operation thereof.

6. In a telephone exchange system, a plurality of lines, each divided into a first and a second section, means associated with each line responsive to signaling current of a certain character incoming over the first sec-

tion thereof, means individual to each of said lines responsive to signals of another character incoming over the second section of each of said lines for controlling the application of signaling current of said certain character to the first sections of said lines, and means common to said lines for controlling the generation and transmission of signaling current of said other character over the second section of each of said lines, said last named means being under the control of said first named means and comprising a vibrator relay.

7. In a telephone exchange system, a plurality of lines each divided into a first and a second section, means associated with each line responsive to signaling current of a certain character incoming over the first section thereof, means individual to each of said lines responsive to signals of a second character incoming over the second section of each of said lines for controlling the application of signaling current of said certain character to the first sections of said lines, and means common to said lines and cooperating with said second means for generating and transmitting signaling current of said second character over the second sections of said lines, said last named means being controlled by said first named means and comprising a vibratory relay.

In witness whereof, I hereunto subscribe my name this 16th day of October A. D., 1924.

HENRY W. O'NEILL.
